DELPHIA, PENNSYLVANIA, A CORPORATION OF PENNSYLVANIA.

DRYING MACHINE.

1,412,594.

Specification of Letters Patent. Patented Apr. 11, 1922.

Application filed December 18, 1919. Serial No. 345,822.

To all whom it may concern:

Be it known that we, THOMAS ALLSOP and WALTER W. SIBSON, citizens of the United States, residing in Philadelphia, in the 5 county of Philadelphia, and State of Pennsylvania, have invented certain new and useful Improvements in Drying Machines, whereof the following is a specification, reference being had to the accompanying drawing.

The invention relates to drying machines, and more especially to such machines employed for the treating of china, crockery, etc. Briefly outlined, such a machine 10 consists of an enclosure which is traversed by a slowly moving, supporting conveyor for the articles to be treated; means for modifying the atmosphere within the enclosure; and propelling means for constantly circulating the drying medium within the enclosure.

The present invention is more particularly directed to a novel propelling means having associated with it a deflecting surface, which, 15 in co-operation with it definitely determines the course of the circulation of the air within the enclosure.

The invention also comprehends certain other novel details of construction and arrangement which will become apparent from 20 the detailed description which follows.

The illustration represents, more or less diagrammatically, a drying machine which is, in a general sense, typical in form, in that it comprises an enclosure 1 having in its end walls openings 2 and 3 through which access may be had, for the purposes of loading and unloading, to the sprocket chain conveyor 4. This conveyor is slowly progressed through 25 the structure over a circuitous path under the guidance of a number of sprockets 5, 5, by any appropriate driving means. In drying apparatus of the type to which the present invention relates, the conveyor is usually 30 provided with a series of pivotally suspended carriers such as shown at 6, 6, upon which the articles to be treated are mounted in any convenient manner.

The interior of the enclosure is divided 35 by a laterally extending U shaped partitioning unit 7 into a central or drying chamber 8 and an auxiliary channel comprising the vertical end branches 9, 10, and a common horizontal connecting branch 11. As will

be noted from the illustration, a portion of 55 the conveyor run passes through the auxiliary channel in order that its carriers 6 may be reached through the openings 2, 3 for loading and unloading.

At the regions of its merger with the vertical components 12 and 13, of the partitioning unit 7, the bottom component 15, is supplemented with inclinations 16 and 17, for a reason to be presently described.

Centrally disposed within the chamber 8, 65 and revolving upon a transverse axis in close proximity and parallel to the bottom 15, is a rotary paddle 20, which is preferably co-extensive in width with the structure, and which may be rotated in either direction by 70 any approved means. By reason of such proximity of the paddle wheel to the bottom 15 of the drying chamber, said bottom becomes effective as a deflecting surface and determines definitely the course of circulation 75 of the air set up within the enclosure in a manner indicated by the arrows in the drawing, when the paddle wheel is rotated in one direction. When the motion of the paddle wheel is reversed, it will be obvious that a 80 similar circulation will be set up in an opposite direction. In either event, it will be seen that the inclines 16 and 17, serve to facilitate the flow of the drying medium within the chamber.

In order to modify the atmosphere in the drying chamber, we have provided a number of heating coil banks 21. These are distributed in the space above the paddle wheel and preferably between adjacent runs of the 90 conveyor. By virtue of such distribution, the coils lie directly in the path of the circulated air, thereby not only heating the same by radiation, but effecting a diversion of the flow in such manner as to produce a 95 uniform distribution and dispersion, so that the articles carried by the conveyor are, as a consequence, evenly dried.

Having thus described our invention, we 100 claim:

1. A drying machine including, in combination, an enclosure; and a paddle wheel therein revolving in close proximity to one of the enclosure walls as a deflecting surface, the latter thus definitely determining the 105 course of the air circulation set up within the enclosure under the propulsion of the paddle wheel.

2. A drying machine including, in combination, an enclosure comprising a drying chamber having its bottom arranged as a deflecting surface, and supplemented with upwardly inclined extensions at the regions of merger with opposite walls; and a centrally disposed paddle wheel revolving in close proximity to the deflecting surface, the latter thus determining definitely the course of the air circulation set up within the enclosure under propulsion of the paddle wheel.
3. A drying machine including, in combination, an enclosure comprising a drying chamber having its bottom arranged as a deflecting surface; a centrally disposed paddle wheel revolving upon a transverse axis in close proximity to the deflecting surface, the latter thus confining the course of the air circulation set up within the enclosure under propulsion of the paddle wheel to a longitudinal direction; and a supporting conveyor tracing a circuitous path within the structure in the same general direction as that of the air circulation.
4. A drying machine including, in combination, an enclosure comprising a drying

chamber having its bottom arranged as a deflecting surface; a centrally disposed paddle wheel revolving in close proximity to the deflecting surface, the latter thus definitely determining the course of the air circulation set up within the enclosure under propulsion of the paddle wheel; and heating devices distributed about the drying chamber in the space above said paddle wheel, and in the path of the air flow.

5. A drying machine including, in combination, an enclosure; U shaped partition means extending transversely across said enclosure to form a drying chamber; and a centrally disposed paddle wheel revolving in close proximity to the horizontal component of said partition means.

In testimony whereof, we have hereunto signed our names at Philadelphia, Pennsylvania, this twelfth day of December, 1919.

THOMAS ALLSOP.
WALTER W. SIBSON.
